ATTORNEY

UNITED STATES PATENT OFFICE.

AARON MYERS, OF HAMILTON, OHIO.

REFRIGERATING-CHAMBER.

SPECIFICATION forming part of Letters Patent No. 291,074, dated January 1, 1884.

Application filed September 15, 1883. (No model.)

To all whom it may concern:

Be it known that I, AARON MYERS, of Hamilton, Butler county, Ohio, have invented certain new and useful Improvements in Refrigerating-Chambers, of which the following is a specification.

This invention pertains to refrigerators, cooling-houses, refrigerator-cars, &c., and has for its object the more perfect utilization of the cooling properties of ice.

The invention relates to the construction of the ice-crib and its immediate accessories.

If ice be placed in a crib in a refrigerating-chamber and well salted, the ice will melt, heat be absorbed from the atmosphere, and a cool chamber be produced. If the water resulting from the melting of the ice be allowed at once to escape from the chamber, its power of absorbing heat will have been wasted, and much more ice will thereby be required to produce a given effect. If the water be caught in a vessel while still in the cooling-chamber, with the intention of allowing it to absorb heat from the air and produce a useful cooling effect, the water will freeze up and no good result. In my invention the water from the melted ice is retained for a considerable length of time, but freezing is guarded against.

In the accompanying drawings, Figure 1 is a vertical transverse section of a refrigerator-car, showing my improved ice arrangement arranged in the distant end of the same; and Fig. 2 is a broken perspective view of the end of the car, exposing the details of the ice arrangement.

In the drawings, A represents the walls of the car; B, the floor of the same; C, the roof; D, the icing-door in the roof over the ice-crib; E, the outlet, which may have a trap, if desired, for the water resulting from the melting of the ice; F, a slatted crib-floor, arranged horizontally some distance above the floor of the car; G, a series of leg-like supports, to which is secured the crib-floor F; H, the front of the ice-crib, reaching from the crib-floor to near the top of the car, and formed of slatted work and wire-cloth; I, a series of metallic shelves or pans, arranged one over the other below the crib-floor, so that water dripping from the crib will fall upon the top shelf, flow downward upon the next shelf, and so on; J, the trough or gutter running lengthwise the

ice-crib below the discharge-edge of the lower shelf, and connected with the discharge-pipe E; K, a series of battens or cleats, secured to the wall of the car, or to furring-strips attached thereto, so as to form a cleated wall for the ice-crib, the cleats reaching from the floor of the crib to the top of the car, or nearly to the top; L, bolts in the legs G; M, slats lining the front of the crib; N, coarse wire-cloth attached to the front of the crib; O, protecting-battens on the front of the crib, outside of the wire cloth; P, vertical projections from the legs G above their upper level, to engage the bottom of the removable front, H, of the ice-crib; Q, the upper one of a series of shelves, having its front edge turned up like a pan, and provided with a rearward slope; R, the second shelf, oppositely disposed beneath the upper shelf, and having less slope; S, T, and U, additional pans arranged similarly to the upper ones, sloping alternately in opposite directions, each succeeding one toward the bottom having less slope than its predecessor; V, the hole through the legs G, supporting the trough J.

The legs G, with the crib-bottom F, the series of pans or shelves, and the trough J are all united into one rigid structure. It is portable, and may be taken from the car when desired. It is of such length as to fill the car sidewise, and is prevented from leaving the end of the car by the slide-bolts L or any other suitable device. After the base-work is in position the portable crib-front H is set upon the legs, engaging behind the projections P, and its upper edge secured to the car wall or roof. The shelves or pans are continuous from side to side of the car, but the solid legs G divide them into short shelves or pans. This division of the pans is not essential, but results from the solid form of the legs G. By this method of construction substantiality is given to pans or shelves of very thin material. Ice being thrown into the crib from the top is liable to become broken and splintered. The wire-cloth N prevents the trifling fragments from being thrown out into the car, but at the same time the slats M receive all of the hard blows from the ice. The front slats, O, which need not be so closely placed as the inner slats, M, protect the cloth from damage by moving freight. The slats K upon the car-

walls protect the car-body from being bruised by the ice, and serve to secure free passages for the air between the car-walls and the ice in the crib. Water from the melting ice drops 5 to the upper pan or shelf, Q, where, in case it becomes stationary an instant, it would freeze. The rapid slant of the upper pan allows this water to drain away rapidly and absorb heat from the atmosphere during its passage, whereby its temperature is slightly increased and the temperature of the atmosphere lowered. The drip-water then drops 10 to the pan R, over which it passes at a lessened velocity permissible, on account of the higher temperature of the water after it has reached this pan. The water then reaches 15 pan S and flows slower and warmer to pan T, and thence to pan U, off of which it drains into the discharge-gutter J, from whence it is led outside the car. By these means it is possible 20 to retain the water in the form of water, and utilize its properties as an absorbent of heat in a chamber already cold enough to freeze the water if stationary. The air of the 25 interior of the car has free access to the exterior of the ice-pile and to the surface of the water pans or shelves. An exceedingly low temperature is secured below the ice-crib, and a rapid movement of the air thus attained in 30 its neighborhood, which, of course, results in a circulation more or less rapid of the entire body of air within the cooling-chamber. In practice I arrange one of these ice-cribs across each end of the car, provided, of course, 35 with proper means of ventilation, whereby the air may be purified as well as refrigerated. I am enabled in the warmest summer weather to take a warm car and reduce its temperature at the rate of over half a degree per minute from 40 the high temperature of summer weather down to near the freezing-point.

By this system of refrigerator-car construction a warm car may be provided with its ice-cribs and have its temperature brought down 45 to the loading-point in an hour or so, whereas by the ordinary construction the proper refrigerating of a warm car requires from twenty-four to thirty-six hours.

The method of construction which I have thought best to illustrate in connection with 50 refrigerating-cars is, of course, adapted for use with almost all kinds of refrigerating-chambers. The rear edges of the shelves do not come in contact with the end wall of the car, and space is left for the vertical passage 55 of the air, the intention being that there shall be no dead-air spaces in the neighborhood of this ice-crib.

I claim as my invention—

1. In a refrigerating-chamber, the combination of an ice-crib with a floor formed of slats or other open-work, a series of shelves below the ice-crib arranged with decreasing slope, as set forth, and an outlet-pipe arranged to receive the water from the lower pan, substantially as and for the purpose set forth.

2. In a refrigerating-chamber, the combination of an ice-crib with a slatted or other open floor, and a slatted or other open front, and a series of draining-shelves arranged below the 70 ice-crib and open at the front for the free admission of air between the shelves, substantially as and for the purpose set forth.

3. In a refrigerating-chamber, the combination, substantially as set forth, of an ice-crib 75 with an open-work bottom and front, a series of draining-shelves arranged below the ice-crib in such manner that the air may circulate freely over them horizontally and past their edges vertically, substantially as and for the purpose set forth.

4. In a refrigerating-chamber, the combination, with the floor and walls of the ice-crib having open-work front to the ice-crib formed of interior slats, of a netting of wire-cloth exterior to said slats, substantially as and for the purpose set forth.

5. In a refrigerating-chamber, the base structure for the ice-crib, consisting of the slatted or open floor F, the legs G, and the 90 shelves I, passing through said legs, combined substantially as and for the purpose set forth.

AARON MYERS.
